UNITED STATES PATENT OFFICE.

WILLIAM NICHOLS BEARDSLEY, OF BRIDGEPORT, CONNECTICUT.

DESIGN FOR A FOOT-REST FOR PEDALS.

SPECIFICATION forming part of Design No. 26,160, dated October 6, 1896.

Application filed February 12, 1896. Serial No. 579,083. Term of patent 3½ years.

To all whom it may concern:

Be it known that I, WILLIAM NICHOLS BEARDSLEY, a citizen of the United States, residing at Bridgeport, in the county of Fair-
field and State of Connecticut, have invented and produced a new and original Design for Bicycle-Pedals; and I do declare the following to be a full, clear, and exact description of the same, reference being had to the accompanying drawings, forming a part thereof.

Figure 1 represents a perspective view of the foot-rest; and Fig. 2 is a front elevation of the same, looking in the direction of arrow *a* of Fig. 1.
The leading feature of my design resides in the plate A, the sides of which plate are perforated with the stars D and the double convex openings E. Other openings are also shown, though not absolutely essential, such, for instance, as the circular openings F.

Another feature of the design is shown at the end or curve of the foot-rest, wherein the straight lines A' blend into the upward curves A², which curves form the central projections A³ on the upper and lower edges of said plate. 25 The end of said plate is also provided with the clover-leaf perforation G. The horns H at the rear of said plate or rest, while shown, are not essential features.

What I claim is—

The design for a foot-rest for bicycle-pedals, substantially as herein shown and described.

In testimony whereof I affix my signature in presence of two witnesses.

WILLIAM NICHOLS BEARDSLEY.
